UNITED STATES PATENT OFFICE.

ALPHEUS G. HAWS, OF BERKELEY, CALIFORNIA.

DESIGN FOR A SANITARY DRINKING-FOUNTAIN.

59,473.

Specification for Design.

Patented Oct. 25, 1921.

Application filed November 1, 1920. Serial No. 421,194. Term of patent 14 years.

To all whom it may concern:

Be it known that I, ALPHEUS G. HAWS, a citizen of the United States, residing at Berkeley, in the county of Alameda and State of California, have invented a new, original, and ornamental Design for a Sanitary Drinking-Fountain, of which the following is a specification.

Referring to the accompanying drawings—

Figure 1 is a top view, in perspective, taken from one end of a sanitary drinking fountain, showing my new design.

Fig. 2 is a side view, reduced, of the same. My new design consists in the elongated

shape of the bowl 1, rising at one end as a relatively narrow, inwardly open half dome 2, overlying the bowl opening at said end, said opening thence extending to the other end and bounded by an inwardly rolled rim 3 with opposing complementary ogee curves converging toward and merging into each other at both ends.

I claim:—

The original design for a sanitary drinking fountain substantially as shown and described.

In testimony whereof I have signed my name to this specification.

ALPHEUS G. HAWS.
